Martin Jackson

UNITED STATES PATENT OFFICE.

MAURICE J. WOHL, OF NEW YORK, N. Y., ASSIGNOR TO M. J. WOHL & CO., INC., OF LONG ISLAND CITY, NEW YORK, A CORPORATION OF NEW YORK.

FEEDING MECHANISM FOR ARC LAMPS.

Application filed June 15, 1921. Serial No. 477,730.

To all whom it may concern:

Be it known that I, MAURICE J. WOHL, a citizen of the United States, and residing at New York city, in the county of Queens and State of New York, have invented certain new and useful Improvements in Feeding Mechanism for Arc Lamps, of which the following is a specification.

This invention relates to improvements in the feeding mechanism for multiple arc lamps and especially to the equalizing means employed therefor. It embodies particularly improvements of the feeding mechanism shown in the United States Patent for "multiple arc lamps" No. 1,235,271 granted to me on July 31, 1917.

It is the object of the invention to improve the automatic feeding action of the arc lamp by a novel equalizing arrangement.

The details of the invention will be more fully described in the following specification, illustrated by the accompanying drawings forming a part thereof and finally set forth in the appended claims.

In the drawings:

Fig. I is an elevation of the feeding mechanism of a duplex arc lamp, partly in section on the line I—I of Fig. II.

Fig. II is a side elevation on the line II—II of Fig. I.

Fig. III is an enlarged detail of the equalizing arrangement shown in Fig. II.

Fig. IV is a plan on the line IV—IV of Fig. III.

Fig. V is a sectional side elevation of Figs. III and IV partly in section on line V—V of Fig. IV.

Fig. VI shows the parts of Fig. V when the lever 33 is in extreme angular position.

Fig. VII shows a type of construction embodying a modification of the improvement shown by Fig. III.

Fig. VIII is a side elevation of yoke 32 with the equalizing springs.

Similar characters of reference indicate similar parts throughout the various views.

The present invention relates particularly to improvements in the feeding mechanism shown in the patent mentioned above and

the characters of the principal elements of the present specification correspond with those of the earlier patent.

Referring to Figs. I and II of the draw-

ings, 14 is the solenoid of a duplex arc lamp which operates the laminated core 29. The lower end of core 29 carries a yoke 32 which consists of a horizontal, flat and rigid bar, whose ends 37 are bent vertically downward and provided with slots 38 (see Fig. VIII). These slots accommodate the projecting ends 39 of three flat springs, of which the lower two form a laminated couple 31 and are fastened by means of a vertical shouldered pin 40 and cotter pin 41 to dash pot 15 and hold the same in axial alinement with core 29. The third, uppermost spring 30 is fastened by means of rivets 4 to horizontal cross bar 33 which extends perpendicularly to yoke 32 and holds the center of gravity of this bar likewise in axial alinement with core 29 and dash pot 15. The free ends of cotter pin 41 are bent upward after insertion, to embrace the edges of springs 31 and to prevent rotation of the dash pot about its vertical axis. The plunger 20 of dash pot 15 is held in stationary position and axial alinement by means of rod 21 on bar 22 and this bar is suspended by rods 28 from the supporting plate 27 of solenoid 14. The forked outer ends of cross bar 33 hold the longitudinally expandible clutch-lifting bars 36 whose upper forked ends guide the lower end of 35. The clutches 16 consist of two parallel and normally horizontal plates. The heel of the upper plate is hinged to bar 36 and to two small vertical plates 11 by a cotter pin. The lower clutch plate is hinged at its heel to plates 11 by a second cotter pin. The plates are separated from each other by a projection 12 on the lower face of the upper plate near its toe end, in such a manner that the plates always remain parallel to each other. The carbon-holding rods 17 are held by these clutches in familiar manner. In Fig. VII a modified cross-bar suspension is shown; in this construction the bar 33 is provided with a central aperture which accommodates the neck part of dash pot 15 somewhat loosely and the dash pot is suspended on two laminations in the same manner as previously described.

To illustrate the advantages gained by the invention it should be stated that in duplex arc lamps it is practically unattainable, even with the highest mechanical precision,

that the two clutches on either side of the solenoid axis always grip their carbons at the same instant, unless the carbon rod 17 diameters are exactly alike and the clutches 5 are supported by links 34 of precisely the same length from bar 33. The clutches will open more or less according to the size of rods 17 or of the carbons in lamps in which these are directly clutched. A small diameter carbon will be gripped at a later interval than one of larger diameter and thereby cause a smaller arc in the first instance and a longer arc in the latter. When the lamp 10 is ready to feed, the clutch bars on the smaller carbon, having opened the greatest distance before gripping the carbon, will rest on plate 24 firstly, and unless bar 33 is able to yield, the smaller carbon will feed first and the other carbon will continue to 15 burn, and burn until its very long arc causes it to break.

The construction shown in my previous patent is not able to overcome this defect, and it developed that during its action, 20 when the weight of one of the carbons is removed from bar 33 and this bar is not mounted entirely independent of the dash pot, the latter immediately tends to bind on its plunger as illustrated by the dash and 25 dot lines of Fig. VII and further descent of the core and its parts ceases and both arcs continue to burn until they are too long 30 to sustain themselves and the lamp breaks its arcs and strikes all over again.

Now should bar 33 be made so as to yield, the lower bar of the clutch gripping the smaller carbon rests on plate 24 for the reason given before, then core 29 and bar 33 in 35 their descent will allow the yielding bar 33 due to the weight of the smaller carbon and 40 holders having been removed, to lower its opposite end, thereby bringing the clutch gripping the larger carbon on its plate 24 and as the entire movement continues its descent the two clutches will release and feed 45 their carbons.

The present invention removes this defect entirely and has other advantages besides. Fig. VI shows clearly that bar 33 50 may form a considerable angle with the horizontal line without exerting any influence on the dash pot or disturbing its vertical alinement, which takes place in the modification Fig. VII or in case all three 55 springs are united by pin 40. In operation, especially on alternating current, the core vibrates violently and the equalizing springs 31 and 30 are intended to prevent the transmission of these vibrations to the arcs. In 60 the previous constructions all equalizing springs were under a vertical tension between the lifting solenoid and the dash pot, while in the new construction spring 30 which carries 33 is independent of such tension and therefore still less subject to the 65

transmission of vibrations and arm 33 is in a floating position which produces an extremely gentle working of the feeding mechanism.

Having thus described my invention, what 70 I claim as new and desire to secure by Letters Patent is:

1. In an arc lamp a pair of electrodes, lifting means therefor, a cross-bar connecting said lifting means to each other, magnetic means, a dash pot having a fixed and a movable member in axial alinement with said magnetic means, a joint including resilient means permitting longitudinal movement between said dash pot and said magnetic means and other resilient means on 80 said joint holding the substantially equal lever arms of said bar balanced and yieldingly connected to said magnetic means.

2. In an arc lamp a solenoid having a 85 core, holding means on said core, a dash pot consisting of a fixed and a movable member in axial vertical alinement with said core, a cross-bar having substantially equal lever arms balanced about a line horizontally 90 intersecting said axis by electrode lifting means operated at each end of said bar, resilient means to hold said bar normally horizontal and other resilient means to join said dash pot by said holding means to said core. 95

3. In an arc lamp a frame, a dash pot and a solenoid held thereby, a core in said solenoid, a yoke on said core holding a plurality of flat springs suspended at their ends, a cross bar, electrode lifting means operated 100 by said bar, one of said springs being connected to the middle portion of said cross-bar and the other springs to the movable part of said dash pot.

4. In an arc lamp a frame, a dash pot and magnetic operating means held above the same, a resilient joint between said dash pot and said magnetic means consisting of a yoke and a plurality of flat springs suspended 105 at their ends by said yoke some of said springs being connected to the movable part of said dash pot, another spring holding a lever in equilibrium at right angles to said yoke and electrode lifting means at the end of substantially equal arms of said lever. 110

5. In an arc lamp a resilient expansible joint adapted to form a connection between two vertically movable members and a horizontal tiltable cross-bar, said joint consisting of a rigid yoke connected to one of said movable members having its ends bent vertically, a plurality of flat springs held in slots of said ends, the other movable member being connected to some of said spring and the remaining springs being connected at right angles to said bar to permit the latter to move vertically and to tilt simultaneously while said movable members move towards or away from each other. 115

6. In an arc lamp having a dash pot and 120

magnetic operating means in axial vertical springs to form an axial pivot for said dash alignment with each other, a resilient joint pot and a transverse cotter pin penetrating between said dash pot and said magnetic an extension of said dash pot and said stud 10 means, said joint consisting of a flat horizontal bar having its ends bent vertically, and forming means to prevent the rotative flat springs held by said ends parallel to movement of said dash pot when its ends are said bar, a stud rotatably held in said bent upward to embrace said springs.

MAURICE J. WOHL.
